SOLVENT REFINING OF MOTOR FUELS

Wilbur B. Pings, Wilmington, Del., assignor to
E. I. du Pont de Nemours & Company, Wilming-
ton, Del., a corporation of Delaware

No Drawing. Application June 30, 1939,
Serial No. 282,072

17 Claims. (Cl. 196—13)

This invention relates to the solvent refining of motor fuels and more particularly to the production of motor fuels of relatively high knock rating from motor fuels having relatively low knock rating.

Motor fuels derived from crude petroleum oils by direct distillation, known as straight-run gasolines, are in general too low in octane value to be used per se in the high compression engines of today. These fuels, as well as the cracked gasolines and polymer gasolines, are ordinarily composed of mixtures of paraffinic, naphthenic, aromatic and unsaturated aliphatic constituents which vary widely in their resistance to knocking in high compression internal combustion engines. It is generally desirable to improve the knock rating of such motor fuels or to obtain therefrom motor fuels of higher knock rating. I have found that, by solvent refining such motor fuels employing a certain type of solvent, I can separate, from such motor fuel mixtures, the constituents of relatively high knock rating.

It is well known that the more viscous petroleum oils can be refined by means of solvents to separate the relatively non-paraffinic constituents from the relatively paraffinic constituents. Many solvents have been proposed therefor and have been employed successfully. Many of such solvents cannot be employed with the non-viscous oils of motor fuel boiling range, as they will not form the essential two phases at obtainable temperatures, or cannot be separated from the several fractions of the motor fuel.

It is an object of my invention to provide a method of treating a non-viscous, normally liquid hydrocarbon oil of motor fuel boiling range containing relatively paraffinic and relatively non-paraffinic hydrocarbons to separate the relatively non-paraffinic hydrocarbons from the relatively paraffinic hydrocarbons. Another object is to extract the relatively non-paraffinic hydrocarbons from a non-viscous, normally liquid hydrocarbon oil of motor fuel boiling range by means of a selective solvent. A further object is to provide a method of producing a motor fuel of improved knock rating from a non-viscous, normally liquid petroleum oil of motor fuel boiling range, which comprises a mixture of hydrocarbons of different knock ratings by extracting the hydrocarbons of relatively high knock rating therefrom by means of a selective solvent. A still further object is to provide a method of producing a motor fuel of improved knock rating from a straight-run gasoline. Other objects are to improve the art. Still other objects will appear hereinafter.

These objects may be accomplished in accordance with my invention, which comprises subjecting a non-viscous normally liquid hydrocarbon oil of motor fuel boiling range containing relatively

paraffinic and relatively non-paraffinic hydrocarbons to a solvent extraction step, employing as the extraction solvent a di-alkoxyalkyl phthalate in which each alkoxyalkyl group contains only two to six carbon atoms. I have found that such alkoxyalkyl phthalates will extract the relatively non-paraffinic hydrocarbons from such hydrocarbon oil and will extract the hydrocarbons of relatively high knock rating from a non-viscous normally liquid petroleum oil of motor fuel boiling range which comprises a mixture of hydrocarbons of different knock ratings.

The hydrocarbon oils, which may be treated in accordance with my invention, are those generally known as non-viscous normally liquid hydrocarbon oils of low molecular weight which are suitable for use in internal combustion engines. They will generally have the following characteristics:

10% distillation point—not over 200° F.

90% distillation point—not over 395° F.

End distillation point—not over 450° F.

The hydrocarbon oils will generally be of petroleum origin, such as the straight-run gasolines, cracked gasolines, reformed gasolines and polymer gasolines, which oils of petroleum origin will be hereinafter referred to as petroleum oils.

The solvents, to be employed in accordance with my invention, are the di-alkoxyalkyl phthalates in which each alkoxyalkyl group contains only two to six carbon atoms. They are di-alkoxyalkyl esters of phthalic acid. Preferably, the alkoxyalkyl radical or group contains only three to four carbon atoms. Also, the di-methoxyalkyl phthalates in which each alkyl group contains only two to three carbon atoms produce the best results. Amongst the compounds which I have found to be particularly satisfactory are:

Di-methoxyethyl phthalate
Di-methoxypropyl phthalate
Di-butoxyethyl phthalate

The di-methoxyethyl phthalate becomes miscible only at about 90° C. and permits phase separation at temperatures of about 25° C. and lower. The di-methoxypropyl phthalate permits phase separation at about 0° C. The di-butoxyethyl phthalate permits phase separation at about -50° C. and is applicable for extractions at low temperatures. Alkoxyalkyl phthalates of intermediate numbers of carbon atoms will permit phase separation at intermediate temperatures.

In general, the method of my invention will comprise mixing approximately equal volumes of solvent and hydrocarbon oil and heating with agitation to a temperature at which the solvent and oil become completely miscible. The solution will then be cooled with agitation to a temperature substantially below the temperature of

complete miscibility. Upon settling, two layers will be formed, which are then separated, and the motor fuel recovered from each layer by distillation from the solvent, one of which layers comprises components of the motor fuel dissolved in the bulk of the liquid solvent, while the other layer contains the undissolved and relatively low anti-knock constituents in admixture with a relatively small amount of solvent. The motor fuel, from the layer containing the larger amount of solvent, comprises primarily a large proportion of the relatively non-paraffinic hydrocarbons of relatively high knock rating. The hydrocarbons from the layer containing the smaller amount of solvent comprises primarily the relatively paraffinic constituents of low octane number and low knock rating. The motor fuel, from the layer containing the larger amount of solvent, the extract phase, may be employed per se as a high anti-knock motor fuel or it may be used for blending with an ordinary petroleum naphtha to increase the octane value or knock rating of the naphtha. It may be used without further refining, if desired, or it may be subjected to any of the usual refining treatments, such as distillation and the like.

Before subjecting the oil to the extraction treatment, it will generally be desirable to top it of light ends to 95° C., that is, to boil off the constituents boiling below 95° C. This is done to avoid handling losses of gasoline by volatilization, as the light ends are generally satisfactory as to knock rating.

In the example given below, the selective removal of the high anti-knock constituents from a motor fuel has been measured by following the change in refractive index and aniline point of the gasoline. The values of these constants for different hydrocarbon types is described in an article by F. D. Rossini in the Oil and Gas Journal, volume 36, November 12, 1937, page 193 et seq., entitled "A decade of research on the chemical constitution of petroleum." The values of the refractive index increase in the order paraffin, naphthene, and aromatic, and for molecules with 8 or 9 carbon atoms have the following approximate values: paraffin 1.40; naphthene 1.425; aromatic 1.50. The critical solution temperature in aniline increases in the order aromatic, naphthene, and paraffin, and for molecules with about 8 carbon atoms has the following approximate values, respectively: -20° C., 45° C. and 70° C. The aniline points of a large number of pure hydrocarbons will also be found in an article by E. B. Evans entitled "Aniline points of hydrocarbons" in the Journal of the Institution of Petroleum Technologists, volume 23, page 220 et seq. An increase in the refractive index and a decrease in the aniline point will thus indicate a segregation of the desirable types largely responsible for high octane value.

In order to minimize handling losses, selective solvent extraction is preferably applied to gasolines having an initial boiling point of about 200° F. (93° C.), which will in general necessitate a preliminary topping operation.

Example

A straight-run gasoline, with the following characteristics: average molecular weight 106; specific gravity 0.736; sulfur 0.08%; boiling range 100 to 390° F. (38 to 199° C.); octane number 66 (average), was topped of light ends to 95° C. The fraction, boiling above 95° C. (about 66% by weight of the original gasoline) was mixed with

an equal volume of di-methoxyethyl phthalate and heated to 95° C., at which temperature solvent and gasoline were miscible. The solution was cooled to 5° C., allowed to settle, and the two layers withdrawn into separate containers. The gasoline was recovered from both layers by distillation at reduced pressure. The solvent layer was found to contain 8% by volume of the gasoline. The extract had a refractive index at 25° C. of 1.4461, compared with a value of 1.4300 before extraction, and an aniline point of 12.1° C., compared with a value of 43.0° C. before extraction.

The above example is merely illustrative of my invention and my invention is not to be limited thereto. Many variations and modifications may be made in the process and the conditions employed without departing from the spirit of my invention. Also, other di-alkoxyalkyl phthalates may be substituted for the di-methoxyethyl phthalate. Some of such other di-alkoxyalkyl phthalates are:

Di-methoxymethyl phthalate

Di-methoxybutyl phthalate

Di-ethoxymethyl phthalate

Di-ethoxyethyl phthalate

Di-ethoxypropyl phthalate

Di-ethoxybutyl phthalate

Di-propoxymethyl phthalate

Di-propoxyethyl phthalate

Di-propoxypropyl phthalate

Di-butoxymethyl phthalate

Also, di-alkoxyalkyl phthalates, containing two different alkoxyalkyl groups, may be employed. Further, mixtures of two or more different di-alkoxyalkyl phthalates may be used. Further, my solvents may be employed in combination or admixture with other known solvents.

The extraction treatment with my compounds may be applied to a raw distillate or to a partially refined product, as well as to a completely refined product. Under certain conditions, for example in the case of fuels with high sulfur content or undesirable characteristics as regards tendency to form gum, it may be desirable to supplement the extraction with the usual acid, alkali and doctor treatment applied either before or after the solvent extraction. Also, the conditions of the application of the solvent may vary with the nature of the gasoline being treated and the improvement in anti-knock rating desired. It may be desirable to carry out the extraction with a relatively large volume of solvent, for example several hundred percent. In some cases, it may be desirable to carry out the extraction with less than equal volume of solvent. However, approximately equal volumes of solvent and gasoline will usually be employed. The solvent and gasoline may be mixed and separated in a batch operation or in a countercurrent operation. The temperature for the formation of two phases may vary, depending upon the particular gasoline and solvent selected, but will generally range from about -40° C. to about 50° C.

My invention has the advantage of providing stable neutral solvents which will have no tendency to react with the constituents of the gasoline. The solvents have boiling points sufficiently high to permit separation of the gasoline therefrom by a simple distillation. The solvents have miscibility characteristics which permit them to be employed without other materials such as precipitants and the like. As compared with my compounds, other somewhat related alkoxyalkyl esters, such as di-butoxymethyl fumarate, di-butoxymethyl succinate and di-butoxymethyl adipate,

do not form two phases with the gasoline of the example at temperatures even as low as -50° C.

I claim:

1. The method of treating a non-viscous normally liquid hydrocarbon oil of motor fuel boiling range containing relatively paraffinic and relatively non-paraffinic hydrocarbons which comprises extracting the oil in the liquid phase with a di-alkoxyalkyl phthalate in which each alkoxyl group contains only two to six carbon atoms, to separate the relatively non-paraffinic hydrocarbons from the relatively paraffinic hydrocarbons.
2. The method of treating a non-viscous normally liquid hydrocarbon oil of motor fuel boiling range containing relatively paraffinic and relatively non-paraffinic hydrocarbons which comprises extracting the oil in the liquid phase with a di-alkoxyalkyl phthalate in which each alkoxyl group contains only three to four carbon atoms, to separate the relatively non-paraffinic hydrocarbons from the relatively paraffinic hydrocarbons.
3. The method of treating a non-viscous normally liquid hydrocarbon oil of motor fuel boiling range containing relatively paraffinic and relatively non-paraffinic hydrocarbons which comprises extracting the oil in the liquid phase with a di-methoxyalkyl phthalate in which each alkyl group contains only one to four carbon atoms, to separate the relatively non-paraffinic hydrocarbons from the relatively paraffinic hydrocarbons.
4. The method of treating a non-viscous normally liquid hydrocarbon oil of motor fuel boiling range containing relatively paraffinic and relatively non-paraffinic hydrocarbons which comprises extracting the oil in the liquid phase with a di-methoxyalkyl phthalate in which each alkyl group contains only two to three carbon atoms, to separate the relatively non-paraffinic hydrocarbons from the relatively paraffinic hydrocarbons.
5. The method of treating a non-viscous normally liquid hydrocarbon oil of motor fuel boiling range containing relatively paraffinic and relatively non-paraffinic hydrocarbons which comprises extracting the oil in the liquid phase with a di-alkoxyethyl phthalate in which each alkoxy group contains only one to four carbon atoms, to separate the relatively non-paraffinic hydrocarbons from the relatively paraffinic hydrocarbons.
6. The method of treating a non-viscous normally liquid hydrocarbon oil of motor fuel boiling range containing relatively paraffinic and relatively non-paraffinic hydrocarbons which comprises extracting the oil in the liquid phase with a di-alkoxyethyl phthalate in which each alkoxy group contains only one to two carbon atoms, to separate the relatively non-paraffinic hydrocarbons from the relatively paraffinic hydrocarbons.
7. The method of treating a non-viscous normally liquid hydrocarbon oil of motor fuel boiling range containing relatively paraffinic and relatively non-paraffinic hydrocarbons which comprises extracting the oil in the liquid phase with di-methoxyethyl phthalate, to separate the relatively non-paraffinic hydrocarbons from the relatively paraffinic hydrocarbons.
8. The method of treating a non-viscous normally liquid hydrocarbon oil of motor fuel boiling range containing relatively paraffinic and relatively non-paraffinic hydrocarbons which comprises extracting the oil in the liquid phase with di-methoxypropyl phthalate, to separate the relatively non-paraffinic hydrocarbons from the relatively paraffinic hydrocarbons.
9. The method of producing a motor fuel of improved knock rating from a non-viscous normally liquid petroleum oil of motor fuel boiling range comprising a mixture of hydrocarbons of different knock ratings which comprises mixing the oil in the liquid phase with a di-alkoxyalkyl phthalate in which each alkoxyalkyl group contains only two to six carbon atoms, forming an extract phase containing hydrocarbons of relatively high knock rating dissolved in the phthalate and a raffinate phase comprising hydrocarbons of relatively low knock rating, separating the two phases and removing the hydrocarbons from the phthalate.
10. The method of producing a motor fuel of improved knock rating from a straight-run gasoline which comprises extracting the gasoline in the liquid phase with a di-alkoxyalkyl phthalate in which each alkoxyalkyl group contains only two to six carbon atoms to separate the compounds of higher knock rating from the gasoline.
11. The method of producing a motor fuel of improved knock rating from a straight-run gasoline which comprises extracting the gasoline in the liquid phase with a di-alkoxyalkyl phthalate in which each alkoxyalkyl group contains only three to four carbon atoms to separate the compounds of higher knock rating from the gasoline.
12. The method of producing a motor fuel of improved knock rating from a straight-run gasoline which comprises extracting the gasoline in the liquid phase with a di-methoxyalkyl phthalate in which each alkyl group contains only two to three carbon atoms to separate the compounds of higher knock rating from the gasoline.
13. The method of producing a motor fuel of improved knock rating from a straight-run gasoline which comprises extracting the gasoline in the liquid phase with a di-alkoxyethyl phthalate in which each alkoxy group contains only one to two carbon atoms to separate the compounds of higher knock rating from the gasoline.
14. The method of producing a motor fuel of improved knock rating from a straight-run gasoline which comprises extracting the gasoline in the liquid phase with di-methoxyethyl phthalate to separate the compounds of higher knock rating from the gasoline.
15. The method of treating a non-viscous normally liquid hydrocarbon oil of motor fuel boiling range containing relatively paraffinic and relatively non-paraffinic hydrocarbons which comprises extracting the oil in the liquid phase with di-butoxymethyl phthalate, to separate the relatively non-paraffinic hydrocarbons from the relatively paraffinic hydrocarbons.
16. The method of producing a motor fuel of improved knock rating from a straight-run gasoline which comprises extracting the gasoline in the liquid phase with di-butoxymethyl phthalate to separate the compounds of higher knock rating from the gasoline.
17. The method of producing a motor fuel of improved knock rating from a straight-run gasoline which comprises extracting the gasoline in the liquid phase with di-methoxypropyl phthalate to separate the compounds of higher knock rating from the gasoline.

CERTIFICATE OF CORRECTION.

Patent No. 2,221,846.

November 19, 1940.

WILBUR B. PINGS.

It is hereby certified that error appears in the printed specification of the above numbered patent requiring correction as follows: Page 3, first column, line 31, claim 3, for "no-paraffinic" read --non-paraffinic--; line 64, claim 7, for "an" read --a--; and second column, line 69, claim 17, for "improced" read --improved--; and that the said Letters Patent should be read with this correction therein that the same may conform to the record of the case in the Patent Office.

Signed and sealed this 24th day of December, A. D. 1940.

(Seal)

Henry Van Arsdale,
Acting Commissioner of Patents.
